UNITED STATES PATENT OFFICE.

JOHANN JACOB KEYSER, OF AARAU, SWITZERLAND.

SUPPORTING MEANS FOR SPINDLES IN SPINNING MACHINES AND THE LIKE.

Application filed December 8, 1923, Serial No. 679,479, and in Germany July 14, 1923.

This invention has reference to supporting means for the spindles of slubbing, roving, spinning, twisting and similar machines, and it refers in particular to a novel construction 5 of the supporting or journaling beam for the reception and journaling of a plurality of spindles of the kind mentioned, and among other objects and advantages the invention makes provision for a better lubrication of 10 the spindles and to generally improve the journaling and mounting of the same. In the slubbing, roving, spinning and twisting machines, as heretofore constructed the journals of the spinning spindles which were common- 15 ly operated by means of worm wheels or skew wheels, were arranged in separate boxes or casings in such a manner that each spindle was provided with a journaling box of its own and which was secured to the supporting 20 beam. It has already been suggested heretofore to mount all the different journaling and supporting members in a sheet metal box in which the operating shaft with the supporting means for the worm wheels was arranged, 25 and in which the rods for the raising of the ring beam had to be mounted by means of special additional bearing and retaining members. With these previous arrangements there was the inconvenience that the 30 exactness of adjustment of the entire supporting means was interfered with, and on the other hand there was but very imperfect protection against the escape of oil and the entrance of impurities; nor was the lubrication 35 of the spindles and of the gear wheels satisfactory.

With a view of overcoming these drawbacks the supporting beam in accordance with my invention constitutes a closed casing 40 for a plurality of spinning spindles and provided with a continuous depression for the reception of the bottom journals of the several spindles and filled with oil, so as to provide for a very perfect lubrication and 45 for an exact gearing of the spindles. The box shaped beam is preferably constructed so as to serve at the same time as a means of mounting the bearings for the driving shaft, the said bearings being arranged and adjusted 50 in such a manner as to prevent the escape of oil from the casing to the outside. The means for the raising of the lifting rods of the ring beam pass through the casing in such a manner as to be out of contact with the lubricating 55 space. In accordance therewith the supporting and journaling beam is so arranged

and constructed that the fastening means for the several parts do not project outwards through the bottom portion, while on the other hand the beam serves as a carrier in 60 common to all bearings or journals or of other means which are directly supported or guided in the box-shaped beam without any additional supporting members.

An embodiment of the principles of my invention is shown by way of example on the accompanying drawing in which Figure 1 is a transverse sectional view through the box shaped beam, and Figure 2 is a horizontal section through the same. 70

The supporting beam comprises a U-shaped casting 1 the open side of which may be closed by a slide or by a glass plate 2 tightly secured thereto by screws or otherwise.

Within the housing 1 a plurality of spindles 3 is supported by lower ball bearings 4 and upper ball bearings 5. The bearings 5 are transversely held by springs 19 arranged in a casing which comprises a collar 7 attached to the housing 1 and a cover 6 tightly 80 screwed on collar 7.

The bottom ball or foot bearing 4 is mounted in a depression 8, and under each ball bearing 4 a separate cavity 9 is provided for the reception of the lubricant. The lubricant is 85 filled into the beam only slightly beyond the height of the depression 8, so that the gearing of the spindle is only very little immersed into the oil, while when running the spindle propels the oil up to the gearing of the worm 90 wheel or the like 10. The bearings 11 for the shaft 12 of the wheels 10 should be carefully adjusted, in order to produce smooth running of the machine. With this end in view the bearings are supported by screw threaded 95 studs 13 by the intermediary of a groove 14, the bearing being forced against the stud by the drip-lubricator 15. It is of importance in this connection that the holes 16 for the reception of the stud 13 in the casing 1 do not extend 100 through the walls of the casing, as otherwise there would be an impossibility of tightening the casing against leakage of oil.

The so called poker rods 17 on which the usual ring rail is mounted which carries a 105 spinning ring for its spindle are guided in lateral lugs 18 of the wall of the housing 1 so as to preclude any contact of the rods with the lubricant being within the lubricating channel. These ring rails are well known to those 110 familiar with the art and have thereof not been illustrated in the drawing. The inven-

tion has been described in its broad aspects only, and it should be understood that in the practice of my invention it is susceptible of modifications and changes to better adapt the 5 same to existing conditions, and without deviating from the spirit of my invention, as pointed out and set forth in the claim hereunto appended.

I claim:—

10 A spindle bearing and lubricating structure for spinning and twisting machines comprising a casing having an integral bottom wall constituting a depressed lubricant channel and a plurality of spaced lubricant cavities 15 communicating therewith at their upper ends, a plurality of spindles supported in and by the said casing, actuating worms on the said

spindles extending into the said lubricant channel and being adapted to lift lubricant therefrom upon being rotated, a plurality of 20 worm gears engaging with the spindle actuating worms at a point supplied with lubricant from the said channel by and upon rotation of the said spindles and being arranged at such a level as to be out of contact with the lubricant 25 that may be on the said bottom wall, a supporting and actuating shaft for the said worm gears, upper resilient bearings for the said spindles and lower spindle bearings at the junctions of the said lubricant channel 30 and the said lubricant cavities substantially as and for the purpose described.

JOHANN JACOB KEYSER.
